UNITED STATES PATENT OFFICE.

HARRY Z. WHITE, OF BUFFALO, NEW YORK.

DESIGN FOR A GLASS SPARK-PLUG INSULATOR.

57,028.

Specification for Design.

Patented Jan. 25, 1921.

Application filed April 29, 1920. Serial No. 377,724. Term of patent 14 years.

To all whom it may concern:

Be it known that I, HARRY Z. WHITE, a citizen of the United States, residing at Buffalo, in the county of Erie and State of New York, have invented a new, original, and ornamental Design for Glass Spark-Plug Insulators, of which the following is a specification, reference being had to the accompanying drawings, forming part thereof.

Figure 1 is a view of a central glass spark plug insulator showing my design as it appears in elevation.

Fig. 2 is a longitudinal medial section of the same.

I claim:

The ornamental design of a glass spark plug insulator as shown.

HARRY Z. WHITE.
